ABSTRACT OF THE DISCLOSURE

A photocell assembly wherein a photocell is held within an insulated housing by retaining flanges and the wire leads are wrapped around locking ears formed on a downwardly extending plug section to positively secure the photocell to the housing as well as to form the terminals for a plug and socket electrical connection.

Where an electrical component, such as a photocell, must be accurately and securely positioned within an enclosure, the installation is often a time-consuming operation. In conventional designs, the component and associated wire leads are usually attached by bolts, screws or other similar means to a mounting surface that is in turn secured to the main assembly. After mounting, the photocell is electrically connected, in the main assembly area, by soldering or manually attaching the lead wires to an appropriate power supply.

The present invention overcomes the aforementioned problems by providing a photocell unit that may be totally assembled in a remote location and that can be easily mounted and electrically connected without additional parts or operations. The photocell is mounted on the base of an insulated housing having deflectable retaining flanges that secure the photocell body against axial and lateral movement. Retaining the cell in this manner eliminates much of the time normally spent in a mounting operation and allows the use of a smaller photocell base. The photocell leads are then wrapped around locking ears formed on a downwardly extending plug section. In addition to providing additional support for the photocell body, the leads and locking ears cooperate to form an electrical plug that, without additional operations, may be easily inserted into a suitably shaped electrical receptacle. Mounting shoulders are provided on the housing so that the photocell assembly may be inserted into a suitably shaped opening in the main unit and be securely held therein without additional operations or parts. The resulting product is a compact, inexpensive and rugged photocell unit that overcomes the previously mentioned problems.

Accordingly, the objects of the present invention are; to provide a compact photocell assembly that is adapted to be inserted into a socket receptacle; to provide a photocell unit subassembly that can be completely formed prior to installation in a main assembly; to provide an insulated housing for an electrical component wherein the latter is held securely in place on an insulated housing by retaining flanges, and the terminal leads are secured by coiling around locking ears formed on a downwardly extending plug section of the housing; and to provide a photocell unit that can be easily assembled by simple operations.

The above and other objects will be apparent to one skilled in the art upon reading the following detailed description; reference being made to the accompanying drawings in which:

FIGURE 1 is a side cross-sectional view of a photocell assembly made in accordance with the present invention.

2

FIGURE 2 is a top view of the photocell housing shown in FIGURE 1.

FIGURE 3 is a view taken along line 3—3 in FIGURE 1, and

FIGURE 4 is a perspective view of the photocell housing shown in FIGURES 1 through 3.

Inasmuch as the present invention is symmetrically formed, the numbers used in the following description will be understood to also refer to the corresponding symmetrical part.

As shown in FIGURE 1, the photocell assembly 10, in general, comprises a housing 12 and a photocell 14 having wire leads 16.

The photocell 14 used in the present invention may be of any conventional internal design and externally comprises a substantially cylindrical body shell 18 and a disc-shaped base 20. Conventional wire leads 16 of any suitable size and electrically conductive material project downwardly from the base 20 and have a length sufficient for the assembly purposes to be described more fully below.

The housing 12 may be formed of an insulating material such as polypropylene and comprises a mounting plate 24, side walls 26 having retaining flanges 28, and a plug section 30. The mounting plate 24 is substantially circular in shape and has a diameter approximately equal to that of the photocell base 20. The walls 26, formed at the sides of the mounting plate 24, extend vertically a distance approximately equal to the height of the photocell

14. Though having a rectangular cross section in the described embodiment, the wall cross section may be of any shape that will allow sufficient deflection for purposes to be described later. Additionally, a mounting shoulder 31 is formed on the walls 26 so that the assembly 10 may be securely retained within a suitably formed opening in the main assembly without any added parts.

The retaining flanges 28 are located on the inner face 32 of each of the walls 26 a sufficient distance above the top surface 34 of the mounting plate 24 so that the resulting arcuate groove 36 between the retaining flanges 28 and the mounting plate 24 is approximately the same height as the photocell base 20 so as to limit vertical movement of the photocell 14. As shown in FIGURE 2, the retaining flange 28 has an arcuate shoulder 38 having a diameter substantially equal to that of the body shell 18 so that, in assembly, the shoulder 38 will partially encircle the body shell 18 to limit lateral movement about the mounting plate 24.

The plug section 30 comprises a centrally located core 40 projecting downwardly from the mounting plate 24 and outwardly extending locking ears 42. Transversely extending terminal notches 46 are formed in the bottom face 44 of the locking ears 42. Similarly, terminal grooves 52 are formed in each of the end faces 48 of the locking ears 42 adjacent the bottom surface 50 of the mounting plate 24. Additionally, recesses 54 having a generally cylindrical contour are molded in the side walls 56 of the locking ears 42 and extend outwardly from the core 40. The terminal grooves 52, terminal notches 46 and recesses 54 comprise the structure for securing the wire leads 16 to the housing 12. Slots 58 are formed in the mounting plate 24 and extend outwardly from a point above the locking ears 42 and core 40 and are spaced a distance apart approximately equal to the distance separating the wire leads 16.

The photocell 14 is assembled to the housing 12 by inserting the wire leads 16 through slots 58 and pressing the photocell 14 downwardly over the outwardly deflecting retaining flanges 28 until the base 20 rests on the top surface 34. In this position, it will be appreciated that vertical and lateral movement of the photocell 14

is limited by the groove 36 and the shoulder 38, respectively.

As shown in FIGURES 1 and 3, the assembly operation is completed by successively bending the wire leads 16 downwardly and outwardly into alignment with and transversely through the terminal notches 46, and upwardly and outwardly into alignment with and transversely across the terminal grooves 52. The length of lead necessary for the above operation may be predetermined or the wire leads can be severed to the appropriate length at the completion of the winding operation. Finally, the wire leads 16 are crimped into the recesses 54 to form terminal depressions 60. In addition to forming the contact terminals for the leads, the depressions 60 take up any slack present in the bending operation to provide a tightly secured photocell assembly.

As shown in FIGURE 3, the photocell assembly can be easily and conveniently electrically connected by inserting the plug section 30 into a suitably shaped receptacle such as an electrical connector 62 having C-shaped locking notches 64 formed in the contact fingers 66. The notches 64 cooperate with depressions 60 to make the electrical contact as well as providing a locking connection between the photocell assembly and the connector.

While but one embodiment has been shown and described, it should be apparent that one skilled in the art could make various modifications and alterations of the present invention. Accordingly, the invention should be limited only by the appended claims.

I claim:

1. A one-piece plastic housing formed of an insulating material and adapted to receive and retain a generally cylindrical electrical component having elongated flexible wire leads, said housing comprising: a mounting section having upwardly extending deflectable retaining means which are adapted to partially encircle and resiliently engage said component to thereby limit vertical and lateral movement of the latter; apertures formed in said mounting section through which said wire leads are adapted to extend; and a plug section extending downwardly from said mounting section and including recessed surfaces into and around which said wire leads are adapted to be wrapped to thereby fixedly secure said component to said housing.

2. The invention as recited in claim 1 wherein said deflectable retaining means comprise a pair of vertically extending wall sections formed at the sides of said mounting section in diametrically opposing relationship, each

of which has a semi-circular inwardly facing retaining flange formed thereon above said mounting section.

3. The invention as recited in claim 1 wherein said plug section includes a centrally located core and outwardly extending locking ears on which said recessed surfaces are formed.

4. The invention as recited in claim 3 wherein said recessed surfaces include grooves formed in the bottom face of said locking ears, and notches formed in the outwardly facing surfaces of said locking ears adjacent said mounting section.

5. A one-piece plastic housing formed of an insulating material and adapted to receive and retain a photocell having a cylindrical body and a circular base from which a pair of elongated flexible wire leads depend, said housing comprising: a substantially circular mounting plate having a pair of vertically extending walls formed at the side thereof in diametrically opposing relationship, said walls including inwardly facing semi-circular retaining flanges spaced above said mounting plate and adapted to partially encircle and resiliently engage said body to limit lateral and vertical movement of the photocell relative to the mounting plate; outwardly opening slots formed in said mounting plate through which said wire leads are adapted to extend; a plug section extending downwardly from said mounting plate and including a centrally located core and outwardly extending locking ears; grooves formed in the bottom face of said locking ears; and notches formed in the outwardly facing surfaces of said locking ears adjacent said mounting plate whereby said wire leads are adapted to be wrapped into and around said notches and grooves to fixedly secure said photocell to said housing with said wire leads and said plug section constituting a connector section for electrically mounting said photocell.
